(57) **CLAIM**

The ornamental design for a wallmounted foam dispenser, as shown and described.

DESCRIPTION

FIG. 1 is a front view of a wallmounted foam dispenser showing my new design;

FIG. 2 is a top view thereof;

FIG. 3 is a right side view thereof; and,

FIG. 4 is an upper right front perspective view thereof.

The left side view is omitted as it is symmetric in appearance to the right side view of FIG. 3.

The bottom and rear views are omitted because they are plain and unornamental and form no part of the subject matter of the claimed design.
